United States Patent Office.

WRIGHT SMITH, OF ST. LOUIS, MISSOURI.

Letters Patent No. 96,046, dated October 19, 1869.

IMPROVED SUPERHEATING-DEVICE FOR STEAM AND OTHER GENERATORS.

The Schedule referred to in these Letters Patent and making part of the same

To all whom it may concern:

Be it known that I, WRIGHT SMITH, of St. Louis, in the county of St. Louis, and State of Missouri, have made certain new and useful Improved Apparatus for Superheating Steam and other purposes; and I do hereby declare that the following is a full and clear description thereof, reference being had to the accompanying drawings, and to the letters of reference marked thereon.

This invention relates to the manner of superheating steam by heated air, and to the manner of returning the air after its utilization for superheating to the furnace-chamber, the feature of said invention being applicable to ordinary boilers, and operating with economy of fuel.

To enable those herein skilled to make and use my said invention, I will now more fully describe the same, referring herein to the accompanying—

Figure 1, as a sectional elevation; to

Figure 2, as a front view of an ordinary stationary boiler and furnace, with an attachment of the devices referring more especially to this invention.

I arrange the boiler A in any of its usual forms, so as to receive heat from the furnace B, the gases of combustion being guided to pass over the bridge-wall C, in the passage D, to the rear end of the boiler, and enter the flues *a*, then passing to the front of the boiler to escape by the chimney or smoke-stack D'.

It is, however, to be understood that the nature of the special features of this invention do not limit the application thereof to the form of furnaces and flues before described, or to any other specific form.

In connection with said boiler A, by the pipe E, I arrange the superheater F, the same having a number of tubes *f*, fitted into proper heads at the ends of the main cylinder of the superheater.

Thus the steam from the boiler A, passing into the superheater, surrounds the flues *f*, and may escape by the steam-pipe G whenever permitted.

In order to heat the steam in the vessel F, as in the nature of this invention, I arrange the hot-air pipes H about at the top of the furnace B, the same receives air at its outer end, where it terminates in the face wall of the furnace, and passes the air to the rear, and then rises and returns to a joint with the rear end of the superheater.

This air-pipe is, by its position, therefore, subject to the heat of the fuel of the furnace, and especially to the heated products of combustion as they pass to the rear of the boiler, and the air in said pipe thus becomes intensely heated, and, passing through the flues *f*, imparts its heat to the steam in the superheating vessel, to dry the said steam and increase its expansive force.

From the superheater the air passes, by a return-pipe, I, to the forward end of the furnace B. The end *i* of said return-pipe is, however, curved so as to deliver the air in the direction of the draught of hot gases from the furnace.

By this means the pressure produced by the tendency to rise in the hot products of combustion aids the discharge of the air out of the return-pipe I, and the air thus returned to the furnace gives up so much of its heat as remains to the combustion at the furnace, thus utilizing the same very fully.

The return-pipe I may deliver the spent air to the smoke-stack or chimney, aiding the draught therein; but in this arrangement the heat in said air, as discharged, is not fully utilized.

The said device is, by its simplicity of form and economy of action and construction, adapted for many purposes in the arts.

Thus, when in the use of an ordinary boiler and steam-pipe, water is carried to the engines or to rendering-tanks for tallow, lards, and so on, by the use of my said superheater, the steam may be dried, and the water, which before was wasted, will be utilized; and lastly, said devices present all the advantages ordinarily achieved by the use of superheaters.

Having thus fully described my said invention, What I claim, is—

1. The furnace B, hot-air pipe H, superheater F, and its tubes *f*, and the return-pipe I, combined substantially as set forth.

2. The return-pipe I, arranged to deliver the air to the furnace B, in the direction of the draught of the hot gases in said furnaces, substantially as set forth.

WRIGHT SMITH.
